UNITED STATES PATENT OFFICE.

JOHN J. LOBERG, OF BRECKENRIDGE, MINNESOTA.

EXHIBITOR FOR RUGS AND THE LIKE.

Application filed May 25, 1925. Serial No. 32,685.

The present invention relates to an exhibitor for rugs, carpets, and the like, and has for its principal object to provide a means of this nature, whereby no floor room will be required for the display of goods which must be extended in order that they may be examined by customers.

Another important object of the invention is to provide an exhibitor of this nature, which may be suspended from the ceiling and has a spring actuated roller associated therewith, about which the goods, such as a rug, carpet or the like may be wound, so as to be supported in an out of the way position.

Another important object of the invention is to provide an exhibitor of this nature, of simple and durable construction, to which the material may be attached in rolls for display or sale and automatically rewound when desired.

With the above and numerous other objects in view, as will appear as the description proceeds, the invention resides in certain novel features of construction, and in the combination and arrangement of parts as will be hereinafter more fully described and claimed.

In the drawing:

Figure 1 is an elevation of the device, embodying the features of my invention, showing the casing associated therewith in section, and

Figure 2 is a detail section, taken substantially on the line 2—2 of Figure 1.

Referring to the drawing in detail, it will be seen that 5 designates a bracket which is fixed to the ceiling and depends therefrom, terminating in a sleeve 6, for receiving a stub shaft 7, disposed laterally of the bracket. A second bracket 8 is fixed to the ceiling and depends therefrom and supports a casing 9 of cylindrical construction, having one end open with a removable closure 10 therefor. A stub shaft 11 is journaled in the casing co-axially therewith. The stub shafts 7 and 11 extend co-axially into a roller 13, which has suitable means 14 thereon for attaching thereto one end of a rug or the like. The stub shaft 11 is fixed to the roller 13 by means of a cotter pin or the like 15. A disc 16 is mounted on the stub shaft 11 within the casing, for rotation with the shaft. A hub 17 is disposed inwardly from the side of the casing 9 and has an annular

series of teeth 18 formed on its periphery. A plurality of pawls 19 are pivotally mounted on the disc 16, for engagement with the teeth 18 on the hub 17. A flat spring is coiled as is indicated at 20, and has one end fixed to the casing as at 21 and the other end thereof suitably attached to the stub shaft 11. When the rug or the like is completely wound about the roller 13, the spring 20 is not under tension, but when the rug is unwound from the roller, the spring is wound under tension. It will thus be seen that the spring 20 normally maintains the rug wound up on the roller. By means of the pawls 19, the rug may be sustained in partial wound condition in relation to the roller, as will be evident to those familiar with the ordinary pawl and ratchet used in the ordinary curtain roll and in other different arts.

From the above description, it will be seen that a plurality and a relatively large number of rugs may be conveniently stored in a salesroom without taking up any floor room, and that these rugs may be displayed to advantage to a customer with very little effort on the part of the salesman, thereby consuming little of his time. Of course, even the customer can pull the rugs down and look at them without the assistance of the salesman.

It is apparent, of course, that the rug as is shown at 25 in the drawing, may have a member 26 adapted for attachment thereto, which would hang down within reach of individuals of ordinary height, in order that the rugs may be easily pulled downwardly.

The present embodiment of the invention has been disclosed merely by way of example, and attains all of the features of advantage enumerated as desirable in the statement of the invention and the above description.

It will be apparent that numerous changes in the details of construction, and in the combination and arrangement of parts may be resorted to, without departing from the spirit or scope of the invention as herein-after claimed or sacrificing any of its advantages.

Having thus described my invention, what I claim as new is:

A display device of the class described including a pair of spaced brackets, adapted to be suspended from the ceiling, a stub shaft in one of the brackets, a casing fixed

to the other bracket, a stub-shaft journaled in the casing, a roller on the stub shafts, a spring mounted in the casing and coiled about the second shaft with its inner end fixed to the second shaft and its outer end fixed to the casing, a disk on the second shaft within the casing, pawls pivoted to the

disk, a hub formed in the casing and having an annular series of teeth with which the pawls are engageable, means for fixing the 10 roller to the second shaft, and means for attaching a rug to the roller.

In testimony whereof I affix my signature.

JOHN J. LOBERG.
